UNITED STATES PATENT OFFICE.

ISAAC F. WILLEY, OF PHILADELPHIA, PENNSYLVANIA.

QUILL AND HOUSING FOR MOISTURE-EXTRACTORS FOR DRYING CLOTHES.

1,253,551.

Specification of Letters Patent. Patented Jan. 15, 1918.

Application filed August 13, 1917. Serial No. 185,944.

To all whom it may concern:

Be it known that I, ISAAC F. WILLEY, a citizen of the United States, residing in the city and county of Philadelphia, State of Pennsylvania, have invented a new and useful Quill and Housing for Moisture-Extractors for Drying Clothes, of which the following is a specification.

My invention relates to a novel construction of quill and housing employed in connection with motor driven extractors or clothes-drying devices of a character generally similar to that shown and described in my pending application filed July 27th, 1916, Serial No. 111,569, in which the basket is located at the upper portion of the machine and driven or rotated from underneath, preferably by means of an electric motor the armature of which acts as a spindle for the basket, and the motor case of which is hung at the top and as heretofore constructed free to vibrate to a greater extent than desirable.

As heretofore constructed, machines of this character have possessed certain disadvantages which it is the object of my invention, generally stated, to overcome by a simplification of parts and the elimination of certain of them which have been found unnecessary.

My present invention comprehends a new and useful construction of the elements which support and maintain the revoluble spindle of the extractor and effect its maintenance within a quill which is itself flexibly supported on the base of the extractor, to the end that the vibration of the motor and basket may be reduced to a minimum and the supporting elements may be so formed and assembled as to be easily disconnected and taken apart to admit of replacement or repairs.

A further object of my invention is to so construct the quill that while the rotation of the spindle is maintained within it, a constant retention and circulation of lubricant for lubricating the spindle are also secured, with the result that the heating of the lubricant is avoided while its effect upon the spindle is constant.

In carrying out my objects, the quill or

flexible bearing in which the spindle runs, which is made preferably of copper or bronze, is of such construction as not only to constitute a lubricant-containing chamber 55 but also effectively to withstand the strains to which it is subjected. It is furthermore provided with a plurality of case-hardened disks upon which it rests and runs, and, in the assemblage of three shown, one of which, 60 the upper, forms a step on which the spindle directly rests, the second is an intermediate washer-like device, and the third disk is interposed between the two others so that they all take up the friction of the spindle. 65

The quill, moreover, is convex-ended and mounted on a concave plate supported on the base of the casing, is centered by a plurality of bolts disposed radially on its axis, and is normally held to a level plane by a 70 plurality of interposed cushioning devices which serve to effect a reduction in its vibration.

My invention further consists in such a construction and assemblage of the various 75 component elements as will permit of their being readily assembled and dismantled without necessitating the employment of skilled labor, and which when once installed will be found to be efficient and reliable 80 under all conditions and to require a minimum amount of attention.

For the purpose of illustrating my invention, I have shown in the accompanying drawings an embodiment of it which is at 85 present preferred by me because in practice it will be found to give satisfactory and reliable results. It is to be understood, however, that the various instrumentalities in which my invention is shown as embodied 90 can be variously arranged and organized and that my invention broadly considered is not therefore limited to the precise arrangement and organization of the instrumentalities which are typified in the construction 95 shown in the drawings and hereinafter described.

Figure 1 represents a central, vertical, sectional view, partly in elevation, of a moisture extractor adapted for drying clothes 100 and embodying my invention.

Fig. 2 represents a fragmentary, central,

2
sectional view, partly in elevation and on an enlarged scale, of the lower portion of the device.

Fig. 3 represents a section on the line 3—3
5 of Fig. 2.

Fig. 4 represents a section on the line 4—4
of Fig. 2.

Similar numerals of reference indicate corresponding parts.

10 Referring to the drawings:—

1 designates my novel construction of moisture extractor or clothes drying device as an entirety, which comprises a hollow base portion 2 and 2^x, adapted to support a housing 3 which incloses or contains a revolvable basket 4, which latter may be made of copper or other wire, preferably heavily tinned, and if desired protected by heavy steel bands, as will be understood from Fig. 20 1. The basket, as is usual, is provided with a cover or lid, not shown, to retain the contained clothes when the basket is rotated at a high speed.

The basket and its adjuncts may be constructed in any usual manner and as the assembling and mounting of them are well understood by those skilled in the art, no further description of them is necessary.

25 My invention relating more particularly to my novel construction of quill, base and motor in which the motor spindle is mounted and runs, a preferred construction of them is the following:—

30 5 designates an electric motor of any preferred type hung at its top so as to be free to vibrate, and provided with a spindle 6, which carries an armature of the usual construction.

The basket 4 being secured to the upper 40 portion of the spindle, the spindle and basket rotate in unison.

7 designates a quill, or journal bearing, Figs. 1 and 2, the base or lower extremity of which is convex as indicated at 8, to conform to the concavity 9 of a bottom plate 45 10, within which it is supported.

The bottom plate 10 is dished out as shown at 11 for retaining lubricant for the bearing faces 8 and 9.

50 12 designates bolts passing through a flange 13 of the bottom plate to securely hold said plate with respect to the base plate 2^x of the extractor, and also to form a closure for the opening 14 in the base member 55 2^x, through which opening the quill projects to bear on the bottom plate 10.

The convex base 8 of the quill is extended radially inward as a projecting ledge or shoulder 15, upon which rests the underside 60 of a flanged disk 16 the body portion 17 of which is so positioned in the lower bore 18 of the bottom of the guide sleeve 23 of the quill 7, as to fit snugly within it.

The lower portion of the spindle 6 rests 65 upon a disk 19, the upper of the series, the

tubular body portion 20 of which engages in the tubular socket 21 in the spindle 6.

22 designates a disk interposed between the disks 16 and 19.

The disks 19 and 22 are preferably of 70 smaller diameter than the spindle 6 and the disk 16. The arrangement of the disks above described results in reducing to a minimum the thrust friction of the spindle.

75 The quill 7, a generally disk-shaped body, is formed with a central, upwardly extending guide sleeve 23, having a bore 24 for the reception of the spindle 6, and the buttons 16, 19, and 22.

25 designates a cup, so to speak, or lubricant containing chamber, consisting of the outwardly and upwardly extending annular wall 26 integral with the lower portion of the sleeve 23, and forming the chamber proper 27, open at its upper portion.

80 28 designates reinforcing radial ribs located in the chamber 27 between the sleeve 23 and the wall 26 of the cup 25. These ribs are spaced apart and extend from the upper open portion to the lower portion of the chamber 27, so as to allow for circulation of the lubricant contained within said chamber.

85 29 designates upper lateral ports and lower lateral ports which extend through 95 the wall of the sleeve 23 at the upper and lower portions thereof and communicate with the annular chamber 27 and with a plurality of internal vertical grooves 31 formed in the inner face of the bore 24 of 100 the sleeve 23.

90 The grooves 31 at the upper portion of the sleeve 23 open into an annular confined groove 32 formed in the inner face of the bore 24, which groove is in communication 105 with the upper ports 29 leading into the annular chamber 27.

The lubricant deposited in the chamber 27 passes downward through the lower ports 30 into the bore 24 to lubricate the disks 110 17, 22, and 19, and thence into the grooves 31 within which it is caused to move upwardly by capillary action due to the revolving spindle 6, thence into the annular groove 32, and through the ports 29 is returned to the chamber 27, with the result that a continuous circulation of the lubricant is effected.

115 33 designates a circumferential outwardly and downwardly extending flange integral with the cup 25 and provided with a plurality of integral enlargements 34 diametrically disposed and together in their entireties paralleling the axis of the quill.

120 35 designates a plurality of radial reinforcing ribs integral with the outwardly extending flange 33 and the wall 26 of the cup 25.

125 36 designates horizontal webs disposed around the outer portions of the quill and 130

affording reinforcements for the enlargements 34 of the flange 33.

The enlargements 34 are recessed or pocketed as at 37, and perforated for the reception of a plurality of vertically extending bolts 39 secured in the base member 2^x and adapted to center the quill with respect to said base 2^x. 40 designates a plurality of cushioning devices preferably rubber disks supported in the recesses 37 and surrounding the bolts 39.

The rubber disks 40 are conveniently confined in the recesses 37 by a plurality of washers 41 and lock nuts 42 screwed on to the bolts 39.

43 designates screws or pins arranged in the upper portion of the bolts 39 to prevent unloosening of the nuts 42 from the bolts 39.

20 44 designates a plurality of stud bolts the lower portions of which are secured in a corresponding plurality of bosses 45 integral with the quill 7. These bolts extend upward and enter the base 46 of the motor housing 5.

48 designates an annular washer surrounding the reduced portions 47 of each of the stud bolts 44 between the base 46, of the housing and the top face 49 of the quill member 7.

The cushioning devices 40 ease the vibration occasioned by the rotation of the spindle 6 and its adjuncts when the spindle is rotated at high speed.

50 designates a pipe tapped into the wall of the cup 25, to supply lubricant from a feed cup 51 to the lubricant chamber 27.

When an electric motor, as shown in Figs. 1 and 2, is employed, I provide a rheostat or controller, not shown, of any usual and conventional type, so that a mechanical brake may be dispensed with, the controller in practice having three points, one to start, one to stop, and one to throw off the current.

If the extractor be driven by a belt, as contra-distinguished from a motor, suitable means which it is unnecessary to illustrate may be employed in connection with the quill member 7, for the attachment of a pulley or similar device.

The coupling of the motor spindle 6 to the motors and basket 4 can as is obvious be effected in many ways. I find the coupling shown in the drawings in which a plurality of stud bolts 44 forms a direct connection between the quill 7 and the motor 5, a good one for the purpose.

The operation of my extractor will be apparent to those skilled in the art. The rotation of the armature of the motor 5 and its spindle 6 effects the rotation of the basket 4, and through the intervention of my novel construction of quill and casing, and the contained friction disks, friction will be re-

duced to a minimum, the liability of the moving parts to become unduly heated will be eliminated, and the continuous circulation of lubricant while the spindle rotates maintained.

Undue or excessive vibration will also be taken care of by the use of the cushioning devices 40 between the quill 7 and the base 2^x.

The disconnecting or dismantling of the parts for the purpose of inspection or repairs, can readily be accomplished because of the simplicity of the mounting and the arrangement of the parts of the quill with respect to the motor 5 and the casing 2, 2^x.

It will of course be understood that other resilient means such, for instance, as springs, may be utilized as cushioning devices in place of the rubber washers shown and described.

Having thus described my invention, what I claim as new and desire to secure by Letters Patent, is:—

1. In a moisture extractor in which are combined a supporting base formed with a concave seat, a housing superposed upon said base, a motor within said base, a revolvable basket within said housing, and a motor spindle for driving said basket,—a quill the lower portion of which is convex and seated in the concave seat of the base and which is formed with an internal lubricant-containing chamber having an axially-disposed upwardly-extending guide sleeve into which the base of the motor shaft is entered and rotates,—and means for supplying lubricant to the chamber of the quill, the interior of the guide sleeve and the motor shaft.

2. In a moisture extractor in which are combined a supporting base formed with a concave seat, a housing superposed upon said base, a motor within said base, a revolvable basket within said housing, and a motor spindle for driving said basket,—a quill the lower portion of which is convex and seated in the concave seat of the base and which is formed with an internal lubricant-containing chamber having an axially-disposed upwardly-extending guide sleeve into which the base of the motor shaft is entered and rotates,—means for supplying lubricant to the chamber of the quill, the interior of the guide sleeve and the motor shaft,—and cushioning means interposed between the quill and the supporting base of the extractor.

3. In a moisture extractor, the combination of a casing the base of which is formed with a concave seat,—an internally-chambered quill having a convex lower exterior portion adapted to rest and rock upon and within said concave seat and formed with a central guide sleeve,—a plurality of supporting disks within the lower portion of the quill,—a motor spindle supported upon

- 2
 said disks and passing through said guide sleeve,—means for balancing the quill with relation to both the motor and the base,—a motor adapted to drive the spindle,—and 5 means for introducing lubricant into the chamber formed within the quill and surrounding the guide sleeve, into said guide sleeve and around said spindle.
4. In a moisture extractor, the combination of a casing,—a housing superposed thereon,—a basket within said housing,—a motor,—a quill within the base of the housing formed with a guide sleeve which forms both within and without its walls a lubricant 10 chamber,—and a spindle connected with the basket, driven by the motor, passing through the guide sleeve of the quill and stepped or superposed upon disks within the bottom 15 of the quill.
5. In a moisture extractor, the combination of a base,—a motor within the base,—a motor spindle,—a quill superposed upon the bed of the base and conformed to rest and rock thereon,—a guide sleeve within the 20 quill for containing lubricant and which forms the bearing for the motor spindle,—and a plurality of disks upon which said spindle rests.
6. A quill for a moisture extractor, 25 formed with a hollow, chambered, lubricant-containing interior, a convex exterior lower face, an upwardly extending axially-disposed guide sleeve formed with radial ports through its walls and with internal vertical grooves or channels,—in combination with the base of the extractor as an entirety, upon the concave bottom of which the convex exterior of the quill rests,—a basket,—a motor adapted to drive the basket,—and a motor shaft driven by the motor, connected with the basket and entered within the guide 30 sleeve as a support,—and a plurality of disks within the quill upon which the spindle rests.
7. A quill for a moisture extractor, 35 formed with a hollow, chambered, lubricant-containing interior, a convex exterior lower face, an upwardly extending axially-disposed guide sleeve formed with radial ports through its walls and with internal vertical grooves or channels,—in combination with the base of the extractor as an entirety, upon the concave bottom of which the convex exterior of the quill rests,—a basket,—a motor adapted to drive the basket,—and a motor shaft driven by the motor, connected with the basket and entered within the guide 40 sleeve as a support.
8. In a moisture extractor,—the combination of a chambered quill formed with a central upwardly-extending guide sleeve internally vertically channeled and formed with radial ports,—a motor spindle mounted within said guide sleeve,—a plurality of disks fitted within the base of the quill upon 45 which the spindle rests,—and means for supplying lubricant to fill the chambered interior of the quill and the channels and ports of the guide sleeve, so as to surround the spindle with lubricant. 50
9. In a moisture extractor,—the combination of a chambered quill formed with a central upwardly-extending guide sleeve internally vertically channeled and formed with an annular groove and also with radial ports 55 certain of which communicate with said groove,—a motor spindle mounted within said guide sleeve,—disks fitted within the base of the quill upon which the spindle rests,—and means for supplying lubricant to 60 fill the chambered interior of the quill, and also the channels, the annular groove, and the ports of the guide sleeve, so as to surround the spindle with lubricant. 65
